UNITED STATES PATENT OFFICE.

HUGH J. RUSSELL, OF UPLAND, CALIFORNIA

LIQUID-FUEL BURNER.

1,027,070.

Specification of Letters Patent. Patented May 21, 1912.

Application filed September 2, 1911. Serial No. 647,336.

To all whom it may concern:

Be it known that I, HUGH J. RUSSELL, a citizen of the United States, residing at Upland, in the county of San Bernardino 5 and State of California, and whose post-office address is Upland, California, have invented certain new and useful Improvements in Liquid-Fuel Burners, of which the following is a specification.

10 This invention relates to liquid fuel burners and has for its object to provide a burner which can readily be attached to and used in connection with the ordinary stove, furnace, stationary engine, locomotives and all 15 places where heretofore various kinds of oils have been used for the production of flame or intense heat for any desired purpose.

A further object is to provide a burner of 20 the class described which is capable of discharging separate streams of oil and steam in position to become intermixed after leaving the burner.

With these and other objects in view which 25 will be apparent as the description proceeds the invention consists of certain novel features of construction and combination of parts, hereinafter fully set forth.

In the accompanying drawings, Figure 1 30 is a side view of the burner. Fig. 2 is a front end view of the same. Fig. 3 is a rear view. Fig. 4 is a sectional view on the line A—B Fig. 1.

In the practice of my invention I provide 35 a burner 5, composed of a preferably rectangular metal bar 6, having longitudinal bores 7 and 8, the latter of which have screw threaded portions 9 and 10 respectively for the reception of pipe sections 11 40 and 12. The sections 11 and 12 are respec-

tively connected to an oil supply and a steam supply (not shown). The free end 13 of the burner is provided with a horizontal slot 14 communicating with the bore 8 and a diagonal slot 16 communicating with the bore 7. It will be noted that the slots 14 and 16 if extended would converge to a common point, but as more clearly shown in Fig. 2 a thin wall 17 separates them at their outer ends. By virtue of this construction the oil and steam issue separately and do not combine until after being projected from the burner. Side plates 18 and 19 secured to the sides of the burner by screws 20 and 21 serve the purpose of closing the open sides 55 of the slots.

Briefly stated the operation of the burner is as follows: The pipe sections 11 and 12 having been connected to a supply of oil and steam, the burner is partially inserted in the fire box of a stove etc., and the oil and steam forced therethrough under considerable pressure.

Having thus described my invention, what I claim is:

An oil burner comprising a rectangular casting having an oil bore and a steam bore, a flat, wide diagonal slot and a flat, wide longitudinal slot communicating respectively with said bores, said slots converging toward each other, but each having a separate discharge outlet, removable side plates for closing the sides of said slots and means for supplying oil and steam to said burner.

In testimony whereof I have affixed my 75 signature in presence of two witnesses.

HUGH J. RUSSELL.
